(57) CLAIM

The ornamental design for a music studio desk set, as shown and described.

DESCRIPTION

FIG. 1 is a Perspective view of a music studio desk set, showing my new design;

FIG. 2 is a front elevation view of the music studio desk set, showing the main desk with the auxiliary desk removed;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front elevation view of the music studio desk set, showing the auxiliary desk with the main desk removed;

FIG. 9 is a rear elevation view thereof;

FIG. 10 is a left side elevation view thereof;

FIG. 11 is a right side elevation view thereof;

FIG. 12 is a top plan view thereof; and,

FIG. 13 is a bottom plan view thereof.

1 Claim, 6 Drawing Sheets
